UNITED STATES PATENT OFFICE.

HENRY B. NEWTON, OF BLOOMINGTON, ILLINOIS, ASSIGNOR OF ONE-HALF TO BELLE PLUMB LEE, OF BLOOMINGTON, ILLINOIS.

CARPET-CLEANER.

1,084,750.

Specification of Letters Patent.

Patented Jan. 20, 1914.

Application filed December 4, 1912. Serial No. 734,933.

To all whom it may concern:

Be it known that I, HENRY B. NEWTON, a citizen of the United States, residing at Bloomington, in the county of McLean and State of Illinois, have invented certain new and useful Improvements in Carpet-Cleaners, of which the following is a specification.

The present invention relates to improvements in carpet cleaners, involving both a sweeping or brushing device for taking up heavy spoil as lint ravelings, paper, pins, etc., and a suction device by means of which the finer particles of dirt or dust may be cleaned from a carpet or rug.

15 The object of the invention is primarily to improve the suction device, especially the construction of the suction nozzle and dust receptacle, in order to furnish a simple, compact, and efficient means by which the dust 20 and fine dirt may be drawn from the carpet into dust compartments in the suction device.

In the accompanying drawings I have 25 illustrated one complete example of the physical embodiment of my invention constructed according to the best mode I have so far devised for the practical application of the principles of the invention.

Figure 1 is a side elevation of a carpet 30 cleaner involving the features of my invention. Fig. 2 is a central vertical sectional view. Fig. 3 is a perspective view of the combined dust receptacle and nozzle. Fig. 4 is a perspective view of the screen. Fig. 5 35 is a perspective view of a base board of one of the bellows. Fig. 6 is a transverse section of the device.

In the preferred embodiment of my invention I employ the suction cleaner in connection with the usual carpet sweeper, and 40 in this connection the rotary brush or sweeper 1 is carried by the shaft 2 which is rotated from the shafts 3 and 4 upon which the traction wheels 5 and 6 are 45 mounted. The shafts 3 and 4 are supported in the sides 7 of the dust box or receptacle 8, and the receptacle is provided with the usual movable trays 9 that may be turned to empty the accumulated dust in well known manner.

50 It should be understood that the shaft 2 and the brush 1 are rotated from the wheels 5 and 6 through the medium of the intermediate wheel 10 in the usual manner.

The shaft 3 is preferably supported in 55 slots 11 in the sides 7 of the dust receptacle,

and a spring 12 provides a flexible bearing for this shaft. This spring allows the wheels 5 to rise if an obstruction is encountered, but insures that the apparatus shall remain close to the carpet, for a purpose to 60 be described.

The dust receptacle 8 is provided with a removable cover 13, which, by means of screws 14, is removably held on top of the dust receptacle.

I employ a plurality of bellows or pumps, one of which is illustrated in section in Fig. 2. These bellows or pumps are located within the cover 13 and over the dust receptacle 8, the base board 15 being rigidly 70 secured above the dust receptacle 8, and projecting beyond the dust receptacle at the front of the device. These bellows or pumps are operated from the shaft 4 which is provided with several cranks 16 to which the links 17 are connected. In Fig. 2 the actuating part of the bellows is illustrated (partly in dotted lines). A link 17 for each pump is pivoted at 18 to the lever 19 which is fulcrumed at 20 on the base board 15. 80 The opposite end of the lever is pivoted to the link 21 secured to the upper board 22 of the bellows.

Assuming that there are three bellows or pumps, the cranks 16 are arranged at intervals of 120 degrees so that the bellows will be operated alternately from the movement of the carpet sweeper over the carpet. Each movable board 22 of the bellows is provided with outwardly opening flap valve 23, 90 and the base board of each bellows is provided with an opening 24.

The three openings 24 of the base boards are adapted to align over the openings 25, 25, 25, of the screen frame 26. This frame is clamped against the under side of the base boards of the bellows, the openings 25 aligning with the openings 24 of the boards, but the openings 25 are closed at the underside of the frame by a foraminous screen 27 of fabric or other suitable material that will not pass dust. The upper side of the frame is provided with a gasket 28, of chamois skin or other material to form a packed joint.

105 The dust receptacle 29 is formed with partitions 30 which divide the receptacle into three compartments 31, 31, 31, and each of these compartments is in communication, through a screened opening 25 with the 110

slotted base board of a bellows, thus forming in reality a part of the pumps or bellows.

At the forward lower edge of the receptacle 29 a nozzle 32 is formed, a wearing plate 33, of metal, being placed on the under side of the nozzle for contact with the carpet or rug to be cleaned. A slot 34 extends the entire length of the nozzle, and above the nozzle the slot merges into a continuous passage 35 extending across the entire front of the box and at the top of this passage are formed valve seats 36, one of which is located in each compartment 31. Upon each valve seat is an upwardly opening intake valve formed of a flexible strip 37 reinforced by a metallic strip 38, one edge 39 of the strip 37 being secured to the valve seat.

It should be understood that the check or intake valves, each permit passage of dust to its own compartment 31, when the bellows is properly actuated.

The dust receptacle and nozzle are readily attached to and detached from the cleaner, by means of the cam levers 40, one of which is pivoted in ears 41 at each end of the box. The levers each have a bent arm 42 provided with end hooks 43 adapted to hook over the pins 44 on the cover 13. In Fig. 3 the clamp 30 is illustrated in released position. In Fig. 1 the hooks are shown engaging the pins, and the cam lever is turned down, thus clamping the dust receptacle tightly against the under side of the bellows base boards.

In Fig. 3 it will be observed that a cleat 45 is attached at the inside of each end of the receptacle and that the partitions 30 do not extend up flush with the top of the sides of the receptacle. The screen 26 is of a size 40 to neatly fit within the receptacle and rest upon the cleats and partitions, but the flexible gasket 28 which extends beyond the frame 26 at all sides, is adapted to be clamped between the upper edges of the receptacle and the under sides of the base boards, (as in Fig. 2) and in this manner the gasket provides an air tight joint between the removable box and sweeper.

In operation it is evident that the rotation 50 of the crank shaft 4 will actuate the bellows or pumps. The movement of the bellows causes a suction through the nozzle which lifts the check valves 37 and draws the dust into the compartments 31, the foraminous 55 screen 27 preventing passage of the dust

through the bellows, but permitting passage of air through the screen, bellows and out through exhaust valves 23. In this manner the check valves 37 are alternately opened or closed to suck or draw the dust into the dust compartments.

The dust compartments are part of the pumps or bellows, and by this construction I am enabled to collect the dust in the pumps by drawing it through the check valves and, 65 by the screen, preventing its passage through the exhaust valves.

Having thus fully described my invention, what I claim as new and desire to secure by Letters Patent is:—

1. The combination in a carpet cleaner of a dust receptacle having a nozzle, and partitions forming compartments, a valve between the nozzle and each compartment, a foraminous screen over the compartments, 75 and a valved bellows complementary to each compartment and located over the screen.

2. The combination in a carpet cleaner of a dust receptacle having a nozzle, and partitions forming compartments, a valve between the nozzle and each compartment, a foraminous screen over the receptacle, a slotted base board projecting over the screen, and a plurality of bellows, complementary to the compartments, of which the base 85 board forms a part.

3. The combination in a carpet cleaner with a suction device, of a dust receptacle having an open top and a cleat at each end, partitions in the receptacle forming compartments, a nozzle common to all compartments, a valve between the nozzle and each compartment, and a removable frame resting on said cleats and having a foraminous screen closing the receptacle.

4. The combination with a carpet cleaner of a plurality of bellows having a common, slotted base board, of a detachable dust receptacle and means for securing it under the slotted base board, partitions forming 100 compartments in the receptacle and a valve for each compartment, a screen, and a nozzle for the receptacle.

In testimony whereof I affix my signature in presence of two witnesses.

HENRY B. NEWTON.
